COMBINED POCKET ASH RECEPTACLE, MATCH-
BOX HOLDER AND CIGARETTE REST OR SIM-ILAR ARTICLE

Angelo C. Antoine, 657 Pinehill Drive,
Mobile, Ala. 36606

Filed Jan. 23, 1969, Ser. No. 15,471

Term of patent 14 years

Int. Cl. D27—03

U.S. Cl. D85—2

Fig. 1.

Fig. 2.

Fig. 3.

Fig. 4.

FIG. 1 is an end, top and side perspective view of a combined pocket ash receptacle, matchbox holder and cigarette rest or similar article, showing my new design with the ash drawer closed;

FIG. 2 is an end, top and side perspective view with the ash drawer open;

FIG. 3 is an end elevational view; and

FIG. 4 is a side elevational view thereof with the ash drawer open.

The broken line showings of a representative matchbox in FIGS. 1 and 2, and of a representative cigarette in FIGS. 2 and 4 are for illustrative purposes only.

I claim:

The ornamental design for a combined pocket ash receptacle, matchbox holder and cigarette rest or similar article, substantially as shown and described.
